UNITED STATES PATENT OFFICE.

CLIFFORD V. BATES, OF CHICAGO, ILLINOIS.

REEL-HOLDER.

1,220,169.

Specification of Letters Patent. Patented Mar. 27, 1917.

Application filed March 24, 1915, Serial No. 16,560. Renewed August 31, 1916. Serial No. 117,958.

To all whom it may concern:

Be it known that I, CLIFFORD V. BATES, a citizen of the United States, residing at Chicago, county of Cook, and State of Illinois, have invented certain new and useful 5 Improvements in Reel-Holders, of which the following is a specification.

My invention relates to certain improvements in reel holders that may be used for 10 various purposes and herein shown in the form of an eyeglass chain reel.

The principal object of the invention is to construct a device of the character described with positive means for locking and 15 releasing the reel. A further object of the invention is to construct such a device which will be operable in any position. Further points of novelty reside in specific details of construction shown in the accompanying 20 drawings, in which—

Figure 1 is a sectional view on the line 1—1 of Fig. 2.

Fig. 2 is a section on the line 2—2 of 25 Fig. 1.

Fig. 3 is a section on the line 3—3 of Fig. 2.

Fig. 4 is a plan view of a modified form of construction.

Fig. 5 is an enlarged perspective view of 30 the guide block.

Fig. 6 is an enlarged view of the shaft.

Referring now more particularly to the drawing, my improved structure comprises a casing consisting of a rear section 8 that 35 is provided with a clasp or pin 9. A peripheral flange 10 is formed near the outer edge of said section and the front section 11 of the casing snugly fits around the flange 10. An opening 12 is formed centrally of the 40 rear section 8 and preferably of angular form to receive the end of a correspondingly shaped shaft, to be hereinafter more fully described. Surrounding the opening 12 is a plate 13 having a series of fingers 14 45 formed integral therewith and projecting at substantially right angles to the plane of the rear section 8. The plate 13 is soldered or otherwise secured to the rear section.

The reel comprises two circumferential 50 flanges 15 and an intermediate section 16 thereby forming a channel. The channel is internally supported by a web 17 which is disposed substantially midway between the flanges. The reel may be formed in any 55 suitable manner and its details of construction are of minor importance.

A hub 18 is formed upon the web 17 of the reel. The reel is mounted upon a shaft 19 the rear end 20 of which is reduced and suitably formed to fit the opening 12, whereby rotation of the shaft relative to the rear section 8 is prevented. 60

Within the reel and lying between the web 17 and the rear section 8 is a coiled spring 21, one end of which is secured to one of the fingers 14 and the outer end secured to the reel near its periphery, as by striking a tongue 22 out of the web 17 and bending the end of the spring about said tongue. A chain 23, or other flexible member, is wound about the reel with one end thereof secured to the reel in any suitable manner and a slot opening 24 is formed in the outer section 11 of the casing through which the chain passes. Upon the outer end of the 70 chain is any suitable form of hook 25.

Mounted upon the web 17, and upon the opposite side thereof from the spring 21, is a guide block designated as a whole by the numeral 26. The guide block is provided with a central shaft opening 27 and upon opposite sides of said opening two recesses are formed as follows:

The recess 28 is formed longitudinally of the guide block by cutting partially through the block from one side but leaving an inclined surface 29 formed near the opposite side of the block from which the cut is started. The angular surface 29 is downwardly inclined toward the center opening 27. A 85 similarly shaped recess 30 is formed in the guide block 26 on the opposite side of the opening 27 from the recess 28 but the recess 30 is cut in from the opposite side of the block so that the inclined surface 31 is in 90 an inverted position relative to the inclined surface 29. The construction of this block will be better understood by referring to Fig. 2 wherein it is shown in section. The outer end of the shaft 19 is provided with 95 a head 32 having oppositely disposed longitudinal grooves 33 and 34 formed therein.

Within the recesses 28 and 30 are the balls 35 and 36 respectively.

The operation of the structure as thus described, is as follows:

The function of the spring is to rotate the reel so that normally the chain 23 will be wound about the reel and the hook 25 will be adjacent the casing. When it is desired 110 to pull the chain out of the casing, and against the action of the spring, by pulling

upon the hook or that part of the chain which protrudes beyond the casing, the reel is rotated and carries the block 26 with it since the block is secured to the web 17.

5 When the chain is pulled from without the casing the block 26 moves contra-clockwise and the balls 35 and 36, as shown in Fig. 1, will be carried around the shaft 19. When the proper length of chain has been pulled 10 from the casing the operator permits the reel to rotate in a clockwise direction, under the action of the spring 21, until one of the balls 35 or 36 drops into one of the grooves 33 or 34, whereupon a ball is wedged between the 15 shaft 19 and the guide block 26, as shown in Fig. 1, and the reel is thus held in a stationary position.

The modification shown in Fig. 4 illustrates a structure intended primarily for an 20 eyeglass chain reel and since such a structure is always secured in a vertical position there is no necessity for more than a single groove 33 in the shaft 32. It is essential, however, that such a structure be capable of 25 operating in substantially any position and to this end I have devised the preferred form of structure herein illustrated.

It is obvious that the modified form of 30 structure shown in Fig. 4, if placed in a horizontal position would be inoperable for the reason that the balls 35 or 36 would not drop into the groove 33. Consequently I have formed the block 26 with inclined surfaces 29 and 30 upon which the balls are adapted 35 to roll whereby they will gravitate toward the shaft 33 irrespective of whether the structure is in a vertical or horizontal position.

In both the preferred and modified forms of structure, an outward pull of the chain 40 will unseat the ball and then by releasing the pull upon the chain the rotary movement of the block 26 will cause the balls to travel to the ends of the slots in the block where they will remain until the chain is completely 45 wound upon the reel or until the rotary movement of the reel is checked sufficiently to allow one of the balls to drop into one of the recesses in the shaft 19.

It is also obvious that the block 26 need 50 not be of the specific forms herein shown, it being only essential that it be so formed that it will confine the ball and thus cause it to travel in a defined path and therefore without limiting myself to specific details of construction, as herein shown.

I claim:

A reel holder comprising a casing, a shaft 55 secured to said casing and provided with a groove having curved side walls of unequal 60 length at one end thereof to receive a check member, a guide block carried by said reel and through which said shaft extends, said 65 guide block being provided with a slot having substantially parallel side walls disposed at approximately a right angle to the longitudinal 70 axis of said shaft throughout their length, a check member movable within said slot, a spring normally tending to rotate the reel in one direction and a flexible member upon said reel adapted to rotate said reel in the other direction.

CLIFFORD V. BATES.
